UNITED STATES PATENT OFFICE.

GUSTAF A. OLIN, OF WORCESTER, MASSACHUSETTS.

SURFACING TOOL.

Application filed April 25, 1924. Serial No. 708,920.

To all whom it may concern:

Be it known that I, GUSTAF A. OLIN, a citizen of the United States, residing at Worcester, in the county of Worcester and Commonwealth of Massachusetts, have invented new and useful Improvements in Surfacing Tools, of which the following is a specification.

This invention relates to improvements in surfacing tools, and has particular reference to a novel and improved tool for use in laterally facing off or surfacing abrasive wheels or the like.

In my co-pending application Serial Number 708,921 filed April 25, 1924, I have illustrated a machine for use in such work, in which the wheel, disk or the like to be surfaced is given a rotary movement about its axis while the surfacing tool is given a movement over the lateral surface of the workpiece in a direction at right angles to the axis of rotation thereof and is also gradually fed in toward the workpiece as the surfacing operation proceeds. The tool forming the subject matter of the present invention is particularly adapted for use with said machine and is illustrated as so used in the application aforesaid.

In performing work of this character, difficulties have been experienced in the past due to the lateral as well as the endwise thrusts imparted to the tool spindle, the changing direction of said thrust impulses, and to the working of abrasive powder resulting from the work into the spindle-bearings, causing rapid wear and deterioration of the parts.

It is the purpose of the present invention to obviate the difficulties experienced with the structures of the prior art and to provide an improved surfacing tool which will satisfactorily resist the several strains to which it is subjected, which will prevent access of abrasive particles to the working parts thereof, and which will permit of ready lubrication and adjustment of the several parts thereof.

A further object of the invention is to prevent breakage of either the tool or the workpiece on account of the usual rigid holding of the parts, which result is accomplished by adapting the parts of the tool for limited relative yielding movement.

One structure for the attainment of these objects is illustrated in the accompanying

drawings. Briefly considered it comprises an outer shell or holder and an inner spindle. Intermediate the spindle and shell are anti-friction bearings to take up the lateral strains directed against the spindle, and in addition end thrust bearings are provided to care for the end thrust of the pressure of feeding the device against the work. In the preferred form of the device the end thrust bearings are resiliently supported to yield under undue strain and thus prevent breaking of either the tool or work. Means are provided to vary the resilient pressure of the bearings so that said pressure may be reduced as desired according to the breaking strain of the other parts so that the pressure will at all times be less than said amount.

The spindle is provided with a head portion for engagement with the surfacing cup or disk, and adjacent said head has annular members interlocking with corresponding members on the shell to form a labyrinth which will permit of free rotation of the spindle but will exclude dust or abrasive particles to a maximum degree. Additional means are provided to protect the bearings from wear, and still other means for preventing any possible wear of the main spindle, and the several parts are so assembled that in case of wear the parts which have become worn may be readily removed and replaced.

Figure 1 is a longitudinal sectional view of the invention.

Figure 2 is a fragmentary sectional view of a modified form of spring adjusting mechanism.

Figure 3 is a detailed view of the nut locking device employed in Figure 1.

In the drawings, the numeral 10 designates the outer shell of the tool having the exteriorly threaded portion 11 at one end and the interiorly threaded portion 12 at the other. Disposed within the shell is the tool spindle 13 having the enlarged portions 14 and 15 near its ends which interiorly fit the tube or bushing 16. This bushing forms a spacer between the collars 17 and 18 of the roller bearings 19-20 which encircle the enlargements 14-15 of the spindle.

The shell 10 has enlarged shouldered recesses 21-22 which receive the outer portion of the roller bearings. A washer 23 preferably of hardened material encircles the en-

largement 24 of the spindle and bears against the forward end of the bearing 19 to provide a seal therefor and retain it in position. A cap member 25 is screwed onto 5 the portion 11 of the shell and has a shoulder 26 engaging the washer and locking it and thus the bearing in position.

Forwardly of the portion 24 the spindle has an enlarged head 27 providing a seat 28 10 for the work engaging cup or disk 29. This cup 29 is designed to engage the workpiece 30 at an angle thereto, as indicated, and to be driven by the frictional engagement thereof with the rotating workpiece, the tool 15 in its travel over the surface of the workpiece exerting a combined twisting or grinding and scraping or gouging action on the work removing the irregularities therefrom to form a final relatively smooth even 20 surface. A suitable screw device such as indicated at 31 may be employed to secure the cup to the head of the spindle. It will also be understood that if desired, in place of depending on the friction drive the spindle 25 may be positively driven, as by application of a driving belt to the head 27 or by mounting of a special belt-pulley thereon.

In any event, to prevent access of the 30 abrasive particles removed during the surfacing operation to the spindle and its bearings, I preferably secure on the head 27 a collar 32 having an annular rib 33 fitting into the groove 34 in the cap 25, the parts in question thus forming a labyrinth 35 permitting of free relative rotation of the parts without friction or binding while excluding the dirt and dust particles.

At the rear, the spindle has a threaded 40 end 35 on which is engaged the nut 36 having a hub portion engaging the inner part of the roller bearing 20 and having an outer portion clamping the washer 37 against the shoulder of recess 22 to properly retain the outer portion of the bearing. The shell has 45 an aperture 38 normally sealed by the screw 39 which permits access to the periphery of nut 36 for adjustment thereof when the device is assembled.

Rearwardly of the nut 36 is a lock nut 50 member 40 having a flange 41 engaging the nut 36. This flange forms a seat for the lineal thrust bearing 42 which encircles the body of the nut. The free face of this bearing is engaged by the spring 43 contained 55 within the cap 44 which screws into the portion 12 of the shell, the pressure of the spring against the bearing being regulated by screwing or unscrewing of the cap for the purpose heretofore described.

60 The nut 36 may be employed as a check or lock-nut to retain the nut 40 in desired position longitudinally of the spindle, and in addition the nut 40 may be slotted as indicated in Figure 3. In this event a screw 65 45 serves to spread the two parts of the nut

at the slot 46 to cause them to bind against the thread on the spindle and resist accidental relative rotation of the parts.

The structure shown in Figure 2 is a slight variation of that just described, in 70 that the nut 47 on the spindle 35 has a hub 48 to engage the inner portion of bearing 20 and a slight flange 49 affording a seat for the thrust bearing 50. The outer edge of this bearing engages the retaining washer 75 51 for the outer portion of bearing 20, while bearing 50 is retained in place on nut 47 by a second lock-nut 52. Spring 53 contained within cap 54 encircles nut 52 and exerts its pressure against the bearing 50. This 80 pressure is controlled both by adjustment of the cap 54 and by variance in the position of its abutment washer 55 as shifted by the screw 56 in the cap. A nut 57 serves 85 to lock the screw in desired adjustment.

From the foregoing it will be seen that the spindle is supported for free rotation on antifriction bearings which will take up both lateral and end thrust strains thereagainst, that the rear bearings are positively 90 sealed against dust and dirt and the front bearing protected to a maximum degree, that the parts are readily accessible for adjustment or replacement and may be lubricated 95 through the apertures 38 and 59.

I claim:

1. A surfacing tool of the character described, comprising a shell, antifriction bearings within the shell, a spindle journaled in said bearings and having one end projecting from the shell to receive a work engaging member, a shouldered portion on the opposite end of the spindle, a thrust bearing cooperating with said shoulder, a cap for the end of the shell proximate to said bearing, and resilient means intermediate the cap and the bearing for yieldingly forcing the bearing against the shouldered portion on the spindle. 100

105

2. A device of the character described, comprising a spindle having a head at one end and a threaded portion at the other, annular antifriction bearings surrounding the spindle at spaced points, a sleeve member enclosing the intermediate portion of the spindle and holding the bearings in spaced relation, a shell enclosing the parts having seats for the bearings, a flanged member adjustably mounted on the threaded portion of the spindle, means for locking said member in adjusted position, a thrust bearing engaging said member, a cap adjustably engaging the shell adjacent said bearing, and a compression spring interposed between the cap and bearing, whereby the pressure of the spring against the bearing is varied by adjustment of the cap with respect to the shell. 110

115

3. A tool for the purpose described, comprising an outer shell having a bearing seat 120

125

near each end and having an exteriorly threaded portion at one end and an interiorly threaded portion at the opposite end, annular bearings in the seats, a spindle 5 journaled in the bearings and having a head at the exteriorly threaded end of the shell and a threaded portion contained within the opposite end of the shell, the head having a bearing-retaining portion, a second bearing 10 engaging member mounted on the threaded portion of the spindle and engaging the bearing to retain the spindle within the shell, a lock member on the threaded portion of the spindle having an annular flange contacting with the bearing engaging member, a thrust bearing mounted on the lock member, a retaining spring therefor, and cap members forming closures for the ends of the shell interlocking with the threaded ends thereof, one of said cap members having a portion engaging the spring and the other cap member interfitting with the head of the spindle, whereby said cap members exclude dirt particles from the interior of the shell. 15 20

GUSTAF A. OLIN.
